UNITED STATES PATENT OFFICE.

MILTON WERTHEIMER, OF BALTIMORE, MARYLAND.

CIGAR-WRAPPING MACHINE.

Application filed May 27, 1922. Serial No. 564,126.

To all whom it may concern:

Be it known that MILTON WERTHEIMER, a citizen of the United States, residing at Baltimore, in the State of Maryland, has 5 invented certain new and useful Improvements in Cigar-Wrapping Machines, of which the following is a specification.

This invention relates to wrapping machines and has particular reference to a 10 cigar-wrapping machine for wrapping cigars in individual wrappers:

One object of the invention is to provide an improved construction of cigar-wrapping machine wherein a cigar may be 15 wrapped neatly and securely in an inner wrapper of tin or other foil, and an outer wrapper of tissue paper.

Another object of the invention is to provide, in a machine of this class, an improved 20 means for twisting the ends of the tissue wrapper.

A further object of the invention is to provide, in such a machine, an improved means which will not only twist the tissue 25 wrapper-ends but will also coil the twisted ends so they will not untwist, and

An additional object of the invention is to provide an improved machine of this character wherein novel means are used for 30 ejecting the tissue-wrapped cigar after the operation of twisting and coiling has been completed.

With the above, and other objects in view, the invention consists in general of certain 35 novel details of construction and combinations of parts hereinafter fully described, illustrated in the accompanying drawings, and particularly set forth in the claims.

The invention is illustrated in the accompanying drawings, wherein,—

Fig. 1. is a perspective showing of the complete machine, the view being taken from the rear.

Fig. 2. shows a plan view of the upper 45 part of the machine, certain parts being broken away.

Fig. 3. illustrates an elevation of the upper part and right side of the machine.

Fig. 4. shows a vertical longitudinal section 50 through the upper part of the machine, looking at the same from the left side, the section being taken on the line 4—4 of Fig. 2.

Fig. 5 illustrates a similar section on the

line 5—5 of Fig. 2, the view being taken as 55 looking from the right side of the machine.

Fig. 6. shows a sectional plan view on an enlarged scale,—the section being taken on the line 6—6 of Fig. 3.

Fig. 7. illustrates an enlarged vertical 60 cross-section on the line 7—7 of Fig. 3.

Fig. 8. shows a sectional side elevation as viewed on the line 8—8 of Fig. 7.

Fig. 9. illustrates another sectional elevation as viewed on the line 9—9 of Fig. 7. 65

Fig. 10. shows a similar view, the section being taken on the line 10—10 of Fig. 7.

Fig. 11. illustrates an inside view of the right hand end twister.

Fig. 12. shows an outside view of the 70 same right hand end twister, and adjacent parts.

Fig. 13. is a side elevation, partly in section, showing a pair of the wrapper-end gripping clamps. 75

Fig. 14. is a partial plan view of the lower jaw, showing the first step in the wrapping operation, many of the parts being omitted for the purpose of more clearly showing the particular parts associated 80 with this operation.

Fig. 15. is a view similar to Fig. 14 but shows the second step in the wrapping operation wherein the ends of the wrapper are twisted. 85

Fig. 16. is a similar view showing the third step in the wrapping operation where the wrapper-ends are bent forward ready for the formation of the coils.

Fig. 17. is a view also similar to Fig. 16 90 but showing the coils completely formed at the opposite ends of the wrapper.

Fig. 18. shows an enlarged detail side view of a portion of the device illustrating the clutch controlling mechanism. 95

Fig. 19. illustrates a sectional plan view of said clutch controlling mechanism,—the section being taken on the line 19—19 of Fig. 18, and

Fig. 20. shows a sectional detail on the 100 line 20—20 of Fig. 18.

In the present manner of illustrating the invention the device has been shown as mounted on a floor stand 10, although the same may obviously be utilized on a bench or other support. At the top of this floor stand is fixed a housing which includes side plates 11, each of which is provided with an 105

arcuate slot 12. Extending through the housing is a horizontal shaft 13, each end of which projects from the sides 11. On these outwardly projecting shaft-ends are mounted supporting arms 14, which extend above the tops of the sides 11, and are connected by a cross rod or brace 15.

These arms 14, are so supported on the shaft 13, that they may rock on the latter and swing at the sides of the slots 12. The arms are provided with bearings 16, wherein is mounted the horizontal drive shaft 17. Concentric with the slots 12 are a series of openings 18, correspondingly spaced in the two sides 11, so that bolts 19, may pass through the respective arms 14 and into selected openings 18, thus holding the arms and said shaft 17 in the desired position in the slots 12. As will be understood later, the purpose of this construction is to provide a species of belt tightener.

At the lower part and front end the housing projects forwardly at each side as shown at 20, so as to form what may be termed a lower or fixed jaw. Supported in this fixed jaw is a shaft 21, whereon is mounted a revoluble roller 22. Secured to the side members 11 by pivot screws 23 are the side members 24 of a movable jaw 25, so that the movable jaw may be free to swing in order that the parts connected with this jaw may assume either the position shown in full lines in Fig. 4, or the position shown in broken lines in said figure. Between the side members 24 there is a horizontal shaft 26, which carries a revoluble roller 27 corresponding in size to the roller 22 and lying, when the movable jaw is closed, directly over the roller 22. Journalized in the side members 11 is a horizontal shaft 28, whose opposite ends carry arms 29 that project upwardly which arms support a revoluble horizontal roller 30,—the arms being connected by a cross bar 31. This roller 30 lies rearwardly from the rollers 22 and 27, and is positioned close to the pivot pins 23. On the shaft 17 is fixed a belt pulley 32 and around this belt pulley is trained a belt 33 which leads from the top of the pulley 32 forwardly over the top of the roller 27, backwardly from under said roller over the top of the roller 30; forwardly from under roller 30 over the top of roller 22, and then backwardly to the under side of pulley 32, this arrangement being clearly shown in Fig. 4.

As shown in Fig. 5 there is fixed on the shaft 17 a pinion 56, which meshes with a gear 34, that is carried on the shaft 13. Referring again to Fig. 4, it will be seen that on the shaft 13 there is also mounted a sprocket 35 which is connected by a chain 36 with a sprocket 37 on a shaft 38, which latter extends transversely of or across the housing. On this shaft 38 is fixed a cam 39 having a cam-groove 40 therein, wherein

travels a roller 41 mounted on the lower end of a rock arm 42. This rock arm 42 is mounted on a rock-shaft 43. At each end of the shaft 43 there is a forwardly extending rock-arm 44, these latter being connected to the arm 42 by half sleeves 45. Extending rearwardly from each of the side-members 24 of the movable jaw 25, is an arm 46, and each of these arms 46 is connected to a respective arm 44 by means of an adjustable link 47.

With this construction it will be seen that rotation of the shaft 17 will effect rotation of the cam 39 and owing to the shape of cam-groove 40 of cam 39 the latter will oscillate the movable jaw between the full and broken line positions shown in Fig. 4. It is to be noted that the jaw 24—25 is first opened for the purpose of placing the cigar and wrapper in position for wrapping and that the jaw then closes until the wrapping operation is completed, after which it again opens for the ejection of the tissue-wrapped cigar.

It will be obvious that, with the opening of the movable jaw, the belt will slacken to a considerable extent, as shown in broken lines in Fig. 4, and in order to eliminate this slackening as much as possible there is provided the following device. Extending rearwardly from the cross bar 31 (see Fig. 5) is a pull rod 48 which passes through a fixed bracket 49 and carries on its rear end a washer 50 which is adjusted longitudinally by the nuts 51. Between the bar 49 and washer 50 is a compression spring 52. Thus the arms 29 and roller 30 are constantly urged backward by the spring 52 against the tension of the belt 33.

In order to eject the wrapped cigars there is provided on the shaft 21, a pair of rearwardly extending fingers 53 which have their extremities curved upward. Depending from each of these fingers is an arm 54, which is connected by an adjustable link 55, with a rock arm 60 which latter is pivotally mounted on the shaft 28, and said rock-arm 60 is formed integrally with an arm 61 (see Fig. 5) carrying a roller 62 which bears against the edge of a cam 63 on the shaft 38. A tension spring 64 normally urges the arm 60 forward and consequently normally holds the fingers 53 depressed. The cam 63 is arranged on the shaft 38 in such timed relation to the cam 39 on the same shaft that the arms 60 are swung rearwardly at the proper instant in the opening movement of the movable jaw 24—25 to bring the fingers 53 into the broken line position in Fig. 4, and thereby eject the wrapped cigar.

At this point it is desired to give the preliminary or first step in the operation of wrapping a cigar in this machine. At the time when the movable jaw is open, the operator places the wrapper with the cigar laid

thereon in the gap between the movable and fixed jaws. The wrapper with the cigar thereon resting on the belt 33, where the latter runs forwardly from the roller 30 to the 5 roller 22. The machine is then started and the closing of the jaw is effected by the cam 39 so that the cigar is gripped between the two oppositely-traveling portions of the belt between said rollers,—the upper stretch of 10 which is traveling rearwardly, while the lower stretch thereof is traveling forwardly, thus a rolling motion is imparted to the cigar and wrapper which rolls the latter around the cigar.

15 At this time, however, the ends of the wrapper project outwardly and horizontally from the sides of the jaws, and unless means be provided for holding these ends, the operation of rolling the wrapper on the cigar 20 would be ineffective to twist said ends. It is to be understood that prior to the insertion of the cigar and wrapper in the machine the cigar is placed on the wrapper, and preferably consists of an inner sheet of foil and an 25 outer sheet of tissue paper, and partly rolled loosely by hand into the approximate shape. Projecting laterally from each side of the housing is a horizontal guide bracket 65 and in each of these guide brackets there 30 is mounted a slidable head 66, from which there projects forwardly an arm 67, the lower half of which arm is continued forwardly to form a downwardly curved finger 68. Pivoted to the arm 67 at the base of the finger 68 is an upwardly curved finger 69, which is normally held closed on the finger 68 by a spring 70 which latter has its upper 35 end attached to a bracket 71, that is mounted on the arm 67, and its lower end attached to the rear end of an arm 72, carried by the finger 69. The fingers 68 and 69 are provided with opposed notches to form, when closed, a twisting opening 73 as best shown in 40 Figs. 3 and 13 of the drawings.

45 Passing vertically through each finger 68 and just forward of the opening 73 is a sliding pawl 74 which is normally held raised by a spring 75 so that its upper end enters a notch 76 in the said finger 69. Projecting 50 rearwardly from each of the heads is a boss 77, to which is pivotally connected one end of a link 78, the other end of said link being connected to the upper end of a lever 79 which is pivoted intermediate its ends to 55 a bracket projecting laterally from the housing at 80. On each end of the horizontal shaft 38 there is a face cam 81 and the lower end of each lever 79 carries a roller 82 which bears against the face of this cam, being held in position by a suitable spring 83. By means of this arrangement, the mechanism including the fingers 68, and 69 which is preferably termed the end-twisting mechanism or wrapper end twisting mechanism, is 60 given a lateral reciprocatory movement to

and from the sides of the jaws. When the operator, as previously described, places the loosely wrapped cigar in the open jaws, it will be found that the end twisting fingers 68—69 are in position closest to the jaws, as 70 in Fig. 14, of the drawings, so that in placing the cigar between the jaws and on the belt 33, the end portions of the wrapper are held by the operator who thus supports the cigar and wrapper while they are slipped between the movable and fixed fingers on each side.

As the movable jaw closes and the cigar and wrapper are rolled to bring the wrapper tightly about the cigar, the ends of the 80 wrapper will be held by the fingers 68—69 from rotation and consequently will be twisted as shown in Fig. 15. While this twisting operation is going on the twisting mechanisms move outwardly as also shown in 85 Fig. 15 until the entire wrapper-ends are twisted at opposite sides of the machine, into a tail.

Cigars as usually manufactured have one blunt end to which the light is applied, the other end being tapered to a more or less acute point. The cigar for which this present machine is specifically intended is of this general shape. In addition cigars vary 90 slightly in length and, even where the cigars are just the same length, some variations in the position of the pointed end will take place in setting the cigars and wrappers in the machine. On this account provisions 95 have to be made for handling the twisted tail at the ends of the cigar, and I will now explain the manner in which the twisted tail is handled at the blunt end of the cigar.

This blunt end, is disposed at all times to the right of the machine and both the 100 fixed and the movable jaws on the right side of the machine are provided with semicircular cigar-end supporting members 84 which, when jaws are closed, constitute a bearing for the blunt end of the cigar. The 105 cigar being longer than the width of the belt 33 will permit the ends of the partially wrapped cigar to enter the members 84.

Each of these bearing halves is provided 110 at its outer end with a septum or dividing wall 85, having a notch 86, centrally thereon through which the twisted wrapper-tail passes. On the fixed jaw beneath the bearing half 84, is a pair of guides 87 between 115 which slides a head 88, having on its inner face a lug 89, the top of which is beveled off as at 90. On top of the head 88 is fixed a plate 91 having an inwardly projecting finger 92 located at the rear of the head 88. Projecting from the lower part of the head 120 88 is a post 93 on which is pivoted the upper end of an adjacent link 94 having its lower end connected to the end of a rock arm 95 fixed upon the shaft 28. Extending downwardly and rearwardly from this shaft is 125

- a rock lever 96 (see Fig. 5) carrying a roller 97 which bears against the edge of a cam 98 fixed on the shaft 38. This cam 98 is so proportioned and positioned that, upon completion of the outward movement of the right hand head 66 the cam 98 acts to raise the head 88. Consequently the tail at the right hand end of the wrapper will be bent to lie flat against, or adjacent, the outer surface of the right side of the jaw. Since the belt 33 continues to rotate the cigar and wrapper this right-side tail will be brought around to engage the finger 92 on plate 91 and the inclined surface 90 of lug 89. Continued rotation of the wrapper and cigar will thus coil the tail-end up into a flat coil such as is shown in Fig. 17, the coil being prevented from spreading in one direction by the lug 89 and in the other direction by the outer surfaces of the bearings 84.
- The manner in which the tail is coiled at the pointed end of the cigar will now be explained. On the left hand side of the machine, each of the jaws is provided with a bearing half 99 constricted at its outer end as at 100, as shown in Figs. 6 to 10 and 14 to 17 inclusive. On the lower jaw there is provided on this side as on the other, a pair of guides 101 for guiding a head 102. This head is also connected by an adjustable link 103 with a rock arm 104 mounted on the outer end of the cross-shaft 28 as shown in Fig. 8, so that the action of the cam 98 on shaft 38 through lever 96 rocks shaft 28 and effects vertical movement of both the head 66 and 102. Extending upward from the head 102 is a fork 105 which has its lower end mounted on a pivot pin 106 so that the upper forked-end may swing to and from the side of the lower jaw. The forked end consists of a thin plate secured to the inner side of the fork member while the upper end of the fork member is bevelled on its inner side as at 107. The fork member is normally held pressed inward by means of a coiled spring 108 disposed between a bracket 109 and the outer surface of the fork member. On the upper movable jaw on this side of the machine there is provided a pair of guides 57 between which slides a head 109 having outwardly projecting lugs 110. Between these lugs is pivoted a wedge member 111 which has its lower end normally held inward by a spring 112. On the upper jaw is also a bracket 113 to which a lever 114 is pivoted intermediate its ends. The forward end of this lever is connected by a link 115 with the upper end of the wedge member 111. It should here be noted that both the upper bearing halves 84 and 99 are carried on the lower ends of slides 116 movable vertically between guides 117 on the upper jaw and normally held downwardly by springs 118, the extent of their downward movement

being limited by stop screws 119. The head 109 is normally held raised by means of a spring 120 having its lower end attached to the end of the lever 114 and its upper end attached to a pin 121, projecting from the slide 116. At 122 there is a bracket through which slides vertically a push bar 123. Connected pivotally to the rock arm 104 on shaft 28, is a threaded rod 124 which passes through a foot 125 formed on the push bar 123. On this rod 124 are nuts 126 which, when the arm 104 swings upward, engage the foot 125 and lift the bar 123 so the latter will contact with the rear end of the lever 114 and by raising said rear end cause downward movement of the forward end together with the wedge member or plate 111, and thus move the parts to the position shown in Figs. 9 and 10.

By this movement the tail end of the wrapper will be held between the fork-end 107 and the wedge plate 111—the fork member 105 being pushed outwardly at this time to prevent jamming of the coiled tail against the pointed end of the cigar and thereby breaking the same. In order to limit the inward movement of the wedge member 111, a stop screw 127 extends through the lower end of this member and bears against the head 109, as clearly seen in Fig. 7. On the fork member is formed a ledge 128 which acts precisely like the beveled surface 90, on the opposite head 88, so that the tail at the left side is also twisted as shown in Figs. 14 and 17, it being observed from the latter figure that the coil is drawn outward away from the pointed end of the cigar.

At this time it is desired to call attention to the fact that by holding the two ends of the wrapper and twisting or rolling the cigar, one end of the wrapper will be twisted left handed while the other will be twisted right handed, as can clearly be seen by reference to Fig. 15. In like manner the coil of the tail on one end is right handed and on the other is left handed.

In an apparatus of this class it is essential that there shall be a pause in the operation at the time the jaws are opened so as to prevent the possibility of the operator having her fingers crushed by the premature closing of such jaws. To this end a certain clutching and unclutching device which is employed will now be described, reference being made to Figs. 1—2—3—18 and 19.

On the shaft 17 is loosely mounted a belt pulley 129 while fixed on said shaft is a male cone clutch-member 130 which engages the other female member 131 of the cone clutch, the latter member being fixed to the pulley 129. On the male member 130 are fingers 132 of stiff spring material. Slidably on the shaft 17 is a locking-member consisting of a conical part 133 which

is engaged by the fingers 132 and the flat part 134. Thus when the conical member 5 be pushed outward from the housing, the clutch member 130 will be forced into tight engagement with the clutch member 131. At the same time the spring fingers 132 will be spread so they may engage on the flat portion 134.

Under these conditions there will be no 10 tendency for the locking member to slip backward toward the housing. The locking member is provided with a shipper groove 135 which is engaged by the forked end 136 of a shipper lever 137 pivoted intermediate its ends to a lug 138 projecting 15 from the housing. Journalled along the side of the stand 10 is a rock-shaft 139 carrying a rock arm 140, which is connected by a link 141 with the lower end of the shipper 20 lever 137.

This lower end of lever 137 being urged inwardly toward the housing by a spring 142, see Fig. 18. Fixed on the shaft 139 is a rock lever 143, which is connected by a 25 vertical link 144 with the central portion of a lever 145 which has its rear end pivoted to a bracket 146 carried on the housing. The front end of this lever lies close to the periphery of one of the cams 81 on the inner 30 face of which cam there is adjustably mounted a dog 147. Slidably longitudinally of the lever 145 and on the free end of the latter is a pawl 148, which is normally held protracted from the end of the lever 35 by a spring 149. Projecting laterally from the pawl is a pin 150 against the forward side of which engages an arm 151 carried by a transverse rock-shaft 152. On this rock shaft is a rock lever 153 which is connected 40 by a link 154 with a pedal 155.

In the operation of this part of the device let it be assumed that the pulley 129 is being driven by a suitable belt. The operator after placing the cigar in position depresses the 45 pedal 155, this retracts the pawl 148 and spring 142 acts to pull the lower end of the shipper-lever 137 inward and thus throws the clutch into clutching position. Through the connection between the lever 137 and the lever 145 the latter drops at this time. When the clutch is engaged the machine 50 begins to move and consequently the cam 81 revolves in the direction of the arrow in Fig. 18. The operation of wrapping previously described now takes place, and upon the cam completing one revolution, the operator, having lifted her foot from the pedal, the dog 147 engages the pawl 148, lifts the lever 145 and through the connection with 55 the lever 137 throws the clutch out.

It is obvious that with heavy machinery there would be a tendency to overrun due to the momentum of the moving parts. To 60 overcome this there is provided on this shaft 65 17 a friction disk 151 which is surrounded

by an adjustable brake band 152 attached to a lug 153 projecting from the right hand arm 14. This brake band 152 can be set up to the proper tightness so that unclutching the drive pulley will bring the machine to 70 rest at the proper points.

There has thus been provided a simple and efficient device of the kind described and for the purposes specified.

Having described my invention, I claim,— 75

1. In a cigar wrapping machine, means to roll a wrapper around a cigar, means to twist the ends of the wrapper into tails, and means to roll the tails into coils.

2. In a cigar wrapping machine, means to 80 impart a rolling motion to a cigar and wrapper whereby the latter is wrapped around a cigar, means to grip the ends of the wrapper, the last mentioned means holding the wrapper-ends against movement during operation of the rolling means whereby the wrapper ends are twisted, and guide means movable into contact with said twisted ends to cause the same to coil into flat spirals.

3. In a cigar wrapping machine, a wrapper rolling mechanism a wrapper-end twisting mechanism, an end coil-forming mechanism, and means to effect operation of the last two mechanisms at predetermined 85 intervals in the operation of the first mechanism.

4. In a cigar wrapping machine, a wrapper rolling mechanism a wrapper-end-twisting mechanism, an end coil-forming mechanism, an ejector mechanism, and means to effect operation of the last three mechanisms at predetermined intervals in the operation of the first mechanism.

5. In a cigar wrapping machine, means to 105 roll a wrapper around a cigar, means to twist the ends of the wrapper into tails, and an ejector operable to eject the wrapped cigar.

6. In a cigar wrapping machine, means to 110 impart a rolling motion to a cigar and wrapper whereby the latter is wrapped around a cigar, means to grip the ends of the wrapper the last mentioned means holding the wrapper ends against movement during operation of the rolling means whereby the wrapper ends are twisted, and an ejector operable to eject the wrapped cigar.

7. In a cigar wrapping machine, means to 115 roll a wrapper around a cigar, means to twist the ends of the wrapper into tails, and an ejector operable to eject the wrapped cigar, and means to stop the operation of the machine automatically after the ejection of the cigar.

8. In a cigar wrapping machine, means to 120 impart a rolling motion to a cigar and wrapper whereby the latter is wrapped around a cigar, means to grip the ends of the wrapper, the last mentioned means holding the wrap- 125

per ends against movement during operation of the rolling means whereby the wrapper ends are twisted, and an ejector operable to eject the wrapped cigar, and means to stop the operation of the machine automatically after the ejection of the cigar.

9. In a cigar wrapping machine, means to effect rotation in one direction of a wrapped cigar, means to twist the two wrapper-ends and means to effect a coiling of the twisted ends in opposite directions.

10. In a cigar wrapping machine, means to effect rotation in one direction of a wrapped cigar, means to hold the wrapper-ends against rotation whereby the two ends will be twisted in opposite directions with respect to the cigar, and means to effect coiling of the twisted ends in opposite directions.

11. In a cigar wrapping machine, means for imparting a rolling movement to a cigar and its wrapper, gripping members for seizing the ends of said wrapper and holding said ends against rotation whereby rolling of the cigar twists the wrapper ends into tails, mechanism connected to the gripping members and arranged to move said members outwardly during the rolling of the cigar, and devices arranged to effect coiling of said tails.

12. In a cigar wrapping machine, means for imparting a rolling movement to a cigar and its wrapper, gripping members for seizing the ends of said wrapper and holding said ends against rotation whereby rolling of the cigar twists the wrapper ends into tails, mechanism connected to the gripping members and arranged to move said members outwardly during the rolling of the cigar, devices arranged to effect coiling of said tails, said devices being movable into and out of position for engaging said tails, and mechanism arranged to move the coiling devices into engaging position subsequent to the twisting of said tails.

13. In a cigar wrapping machine, means for imparting a rolling movement to a cigar and its wrapper, a pair of wrapper end gripping members mounted to reciprocate in alinement with the rolling axis of the cigar, and arranged to hold the wrapper ends against rotation whereby to effect twisting of said ends into tails under the influence of the rolling movement, a pair of tail coiling devices arranged at opposite ends of the cigar and reciprocable into and out of alinement therewith, and mechanism arranged to effect movement of the gripping members away from the cigar position and to effect movement of the coiling devices into alinement upon completion of the twisting operation.

14. In a cigar wrapping machine, a pair of jaws mounted for opening and closing movement, means for engaging a cigar and its wrapper placed between said jaws and

imparting a rolling movement thereto, mechanism for opening and closing said jaws at the beginning and end of the operation, gripping members for seizing the ends of said wrapper and holding said ends against rotation whereby rolling of the cigar twists the wrapper ends into tails, mechanism connected to the gripping members and arranged to move said members outwardly during the rolling of the cigar, and devices arranged to effect coiling of said tails.

15. In a cigar wrapping machine, a pair of jaws mounted for opening and closing movement, means for engaging a cigar and its wrapper placed between said jaws and imparting a rolling movement thereto, mechanism for opening and closing said jaws at the beginning and end of the operation, gripping members for seizing the ends of said wrapper and holding said ends against rotation whereby rolling of the cigar twists the wrapper ends into tails, mechanism connected to the gripping members and arranged to move said members outwardly during the rolling of the cigar, and devices arranged to effect coiling of said tails, said devices being movable into and out of position for engaging said tails, and mechanism arranged to move the coiling devices into engaging position subsequent to the twisting of said tails.

16. In a cigar wrapping machine, a pair of jaws mounted for opening and closing movement, means for engaging a cigar and its wrapper placed between said jaws and imparting a rolling movement thereto, mechanism for opening and closing said jaws at the beginning and end of the operation, a pair of wrapper end gripping members mounted to reciprocate in alinement with the rolling axis of the cigar, and arranged to hold the wrapper ends against rotation whereby to effect twisting of said ends into tails under the influence of the rolling movement, a pair of tail coiling devices arranged at opposite ends of the cigar position and reciprocable into and out of alinement therewith, and mechanism arranged to effect movement of the gripping members away from the cigar position and to effect movement of the coiling devices into alinement upon completion of the twisting operation.

17. In a cigar wrapping machine, a pair of jaws mounted for opening and closing movement, means for engaging a cigar and its wrapper placed between said jaws and imparting a rolling movement thereto, mechanism for opening and closing said jaws at the beginning and end of the operation, gripping members for seizing the ends of said wrapper and holding said ends against rotation whereby rolling of the cigar twists the wrapper ends into tails, mechanism connected to the gripping members and arranged to move said members out-

wardly during the rolling of the cigar, an ejector positioned to act against said cigar, and mechanism for actuating the ejector in timed relation to the opening of the jaws.

- 5 18. In a cigar wrapping machine, a pair of jaws mounted for opening and closing movement, means for engaging a cigar and its wrapper placed between said jaws and imparting a rolling movement thereto, mechanism for opening and closing said jaws at the beginning and end of the operation, gripping members for seizing the ends of said wrapper and holding said ends against rotation whereby the rolling of the 10 cigar twists the wrapper ends into tails, mechanism connected to the gripping members and arranged to move said members outwardly during the rolling of the cigar, and devices arranged to effect coiling of said 15 tails, said devices being movable into and out of position for engaging said tails, an ejector positioned to act against said cigar, and mechanism for actuating the ejector in timed relation to the opening of the jaws.
- 20 19. In a cigar wrapping machine, a pair of jaws mounted for opening and closing movement, means supported by the jaws for engaging a cigar and its wrapper placed between said jaws and imparting a rolling 25 movement thereto, mechanism for opening and closing said jaws at the beginning and end of the operation, a pair of wrapper and gripping members mounted to reciprocate in alinement with the rolling axis of the 30 cigar and arranged to hold the wrapper ends against rotation whereby to effect twisting of said ends into tails under the influence of the rolling movement, a pair of tail coiling devices arranged at opposite ends of the 35 cigar position and reciprocable into and out of alinement therewith, mechanism arranged to effect movement of the gripping members away from the cigar position and to effect movement of the coiling devices 40 into alinement upon completion of the twisting 45 operation, an ejector positioned to act against said cigar, and mechanism for actuating the ejector in timed relation to the opening of the jaws.

- 50 20. In a cigar wrapping machine, a pair of jaws mounted for opening and closing movement, means supported by the jaws for engaging a cigar and its wrapper placed between said jaws and imparting a rolling 55 movement thereto, mechanism for opening and closing said jaws at the beginning and end of the operation, gripping members for seizing the ends of said wrapper and holding said ends against rotation whereby rolling 60 of the cigar twists the wrapper ends into tails, mechanism connected to the gripping members and arranged to move said members outwardly during the rolling of the cigar, an ejector positioned to act against said cigar, and mechanism for actuating the 65

ejector in timed relation to the opening of the jaws, driving means for said mechanisms, and means to interrupt the action of the driving means automatically upon completion of the operation on a cigar. 70

21 In a cigar wrapping machine, a pair of jaws mounted for opening and closing movement, means supported by the jaws for engaging a cigar and its wrapper placed between said jaws and imparting a rolling 75 movement thereto, mechanism for opening and closing said jaws at the beginning and end of the operation, gripping members for seizing the ends of said wrapper and holding said ends against rotation whereby the 80 rolling of the cigar twists the wrapper ends into tails, mechanism connected to the gripping members and arranged to move said members outwardly during the rolling of the cigar, and devices arranged to effect coiling of said tails, said devices being movable into and out of position for engaging said tails, an ejector positioned to act against said cigar, mechanism for actuating the 85 ejector in timed relation to the opening of the jaws, driving means for said mechanism, and means to interrupt the action of the driving means automatically upon completion of the operation on a cigar. 90

22. In a cigar wrapping machine, a pair of jaws mounted for opening and closing movement, means supported by the jaws for engaging a cigar and its wrapper placed between said jaws and imparting a rolling 95 movement thereto, mechanism for opening and closing said jaws at the beginning and end of the operation, a pair of wrappers and gripping members mounted to reciprocate in alinement with the rolling axis of the cigar, and arranged to hold the wrapper ends 100 against rotation whereby to effect twisting of said ends into tails under the influence of the rolling movement, a pair of tail coiling devices arranged at opposite ends of the cigar position and reciprocable into and out 105 of alinement therewith, mechanism arranged to effect movement of the gripping members away from the cigar position and to effect movement of the coiling devices into alinement upon completion of the twisting 110 operation, an ejector positioned to act against said cigar, mechanism arranged to effect movement of the gripping members away from the cigar position and to effect movement of the coiling devices into alinement upon completion of the twisting operation, an ejector positioned to act against said cigar, mechanism for actuating the ejector in timed relation to the opening of the jaws, driving means for said mechanisms, and means to interrupt the action of the driving 115 means automatically upon completion of the operation on a cigar. 120

23. In a cigar wrapping machine; means for imparting a rolling motion to a cigar and its wrapper; and including a housing and jaws adapted to embrace and rotate a cigar; guides projecting laterally from the housing at each side thereof, heads each 125 slideable in the guides on a respective side of the housing, a fixed gripper finger pro- 130

- jecting from each head substantially parallel to said jaws, a movable gripper finger pivoted to each head to cooperate with the fixed finger, springs normally holding the movable fingers closed on the fixed fingers, a cam shaft extending transversely through the housing, a cam at each end of the cam shaft, an operative connection between each head and a respective cam, and means to drive the cam shaft.
24. In a cigar wrapping machine, means to rotate a cigar and the central part of its wrapper about an axis, means to grip the ends of the wrapper and hold them against rotation whereby to twist the wrapper ends into tails, mechanism connected to the last mentioned means to move the same automatically out of operating position upon completion of the twisting; pairs of guides extending away from the axis of rotation of the cigar at each end of the cigar position; a head slidable in each part of guides, means carried by each head for bending the respective tail at right angles to the cigar position, other means associated with the last mentioned means for effecting coiling of the belt tails, oscillating elements connected to said heads for reciprocating, and a cam actuating the oscillating elements and arranged to effect movement of said heads

into position for operation on the tails subsequent to the twisting operation.

25. In a cigar wrapping machine, means to rotate a cigar and the central part of its wrapper about an axis, means to grip the ends of the wrapper and hold them against rotation whereby to twist the wrapper ends into tails, mechanism connected to the last mentioned means to move the same automatically out of operating position upon completion of the twisting; pairs of guides extending away from the axis of rotation of the cigar at each end of the cigar position; a head slidable in each part of guides, means carried by each head for bending the respective tail at right angles to the cigar position, other means associated with the last mentioned means for effecting coiling of the belt tails, oscillating elements connected to said heads for reciprocating, 40 a cam actuating the oscillating elements and arranged to effect movement of said heads into position for operation on the tails subsequent to the twisting operation, driving means common to all the mechanisms, and means to effect automatic stoppage of the driving means upon completion of the operation. 45

In testimony whereof I affix my signature.
MILTON WERTHEIMER.
